UNITED STATES PATENT OFFICE.

ALFRED H. S. SWAN, OF ROCHESTER, NEW YORK, ASSIGNOR TO ROCHESTER STAMPING COMPANY, OF ROCHESTER, NEW YORK, A CORPORATION OF NEW YORK.

VAPOR-LAMP.

1,010,462.

Specification of Letters Patent.

Patented Dec. 5, 1911.

Application filed February 25, 1911. Serial No. 610,939.

To all whom it may concern:

Be it known that I, ALFRED H. S. SWAN, of Rochester, in the county of Monroe and State of New York, have invented certain new and useful Improvements in Vapor-Lamps; and I do hereby declare the following to be a full, clear, and exact description of the same, reference being had to the accompanying drawings, forming a part of this specification, and to the reference numerals marked thereon.

The present invention relates to vapor lamps, such as are used with chafing dishes and cooking utensils of similar character, and has for its object to provide means for regulating the size of the flame opening, readily, and in an efficient manner, whereby the volume of the flame may be controlled.

To these and other ends the invention consists in certain improvements and combinations of parts all as will be hereinafter more fully described, the novel features being pointed out in the claims at the end of the specification.

In the drawings:—Figure 1 is a vertical sectional view of a lamp, embodying my present invention; Fig. 2 is a bottom plan view of the cover and flame regulating mechanism, the supporting plate being removed, and the shutters appearing in closed position; Fig. 3 is a similar view, showing the shutters in open position, and Fig. 4 is a bottom plan view of the cover, with the supporting plate in position.

Similar reference numerals throughout the several figures indicate the same parts.

In the present embodiment, the invention is illustrated as applied to a lamp of the type generally used with chafing dishes, and in this instance comprising a lamp body 1 and font 2 adapted to contain asbestos or other suitable material for holding the light hydrocarbon oils or alcohol, which is the usual fluid employed, the asbestos being retained within the font in the usual manner or any preferred manner.

The lamp body 1 is provided with a suitable cover 3 having a central opening 4 therein. The shutters 5 are pivotally mounted on the cover 3, beneath the opening, as designated at 6, and are arranged between the cover and a plate or carrier 7, to which is pivotally attached the controlling plate 8, the latter being pivoted to the carrier in any desired manner as by a suitable

rivet 9. A stop 10 is provided on the carrier 7 and arranged to engage an opening in the controlling plate 8 to limit the movement of the latter.

In order to provide a simple form of connection between the controlling plate and the shutters, the latter are provided with slotted openings 12, in which engage pins or lugs 13 carried by the controlling plate, suitable openings 14 being formed in the carrier to receive and permit movement of said pins. It will be seen from this arrangement of the parts that as the controlling plate is moved on its pivot 9, in one direction or the other, the shutters will be moved a corresponding distance to adjust them to either open or close the burner aperture 4 in the cover, all of the parts having a free and unrestricted movement.

To effect operation of the controlling plate 75 the latter carries a pair of downwardly projecting fingers 15 between which engages the operating element, which comprises a crank 16 on the rod 17 provided with a handle 18 by means of which it may be rotated. The 80 operating handle and rod are supported in any suitable way as by a bracket 19 attached to the lamp body.

In order to support the parts within the cover, there is provided a plate 20, arranged 85 beneath the controlling plate, but spaced therefrom, and which may be secured within the cover in any convenient manner. The supporting plate 20 is cut-away, as designated at 21, to permit movement of the operating rod, and the fork on the controlling plate, and the cover is also cut-away at 22 to receive the bracket 19.

This construction affords a very simple and efficient mechanism for regulating the 95 volume of the flame to a fine degree, and comprises few parts, which are capable of being readily assembled, and are so arranged that there is little likelihood of their getting out of order.

I claim as my invention.

1. In a vapor lamp, the combination with a lamp body and a cover having an opening therein, of a pair of shutters pivoted to the cover and co-operating to close the opening, 105 and controlling means comprising a pivotally mounted plate having connection with the shutters and movable transversely of the cover to actuate said shutters.

2. In a vapor lamp, the combination with 110

- a lamp body and a cover having an opening therein, of a pair of shutters pivoted to the cover and coöperating to close the opening, controlling means comprising a pivotally mounted plate having connection with the shutters and movable transversely of the cover to actuate said shutters, and a rotatable operating handle adapted to effect movement of the controlling means.
- 10 3. In a vapor lamp, the combination with a lamp body and a cover having an opening therein, of a pair of shutters pivoted to the cover and coöperating to close the opening, controlling means comprising a pivotally mounted plate having connection with the shutters and movable transversely of the cover to actuate said shutters, a fork carried by the plate, an operating handle, and means movable with the handle and coöperating 20 with said fork to actuate the controlling means.
4. In a vapor lamp, the combination with a lamp body and a cover having an opening therein, of a pair of shutters pivoted to the cover and arranged beneath the opening, a carrier positioned beneath the shutters, and controlling means comprising a plate pivotally mounted on the carrier and having connection with the shutters, the controlling 25 means being movable to actuate the shutters.
5. In a vapor lamp, the combination with a lamp body and a cover having an opening therein, of a pair of shutters pivoted to the cover and arranged beneath the opening, slotted portions carried by the shutters, a carrier beneath the shutters having openings arranged opposite the slotted portions thereof, controlling means comprising a plate pivotally mounted on the carrier and 30 pins carried by the plate and projecting through the openings in the carrier to engage the slotted portions of the shutters, said controlling means being movable to actuate the shutters.
- 40 45 6. In a vapor lamp, the combination with a lamp body and a cover having an opening therein, of a pair of shutters pivoted to the cover and arranged beneath the opening, slotted portions carried by the shutters,
- a carrier beneath the shutters having openings arranged opposite the slotted portions thereof, controlling means comprising a plate pivotally mounted on the carrier, pins carried by the plate and projecting through the openings in the carrier to engage the slotted portions of the shutters, the controlling means being movable to actuate the shutters, and a plate for supporting the carrier and controlling means.
7. In a vapor lamp, the combination with a lamp body and a cover having an opening therein, of a pair of shutters pivoted to the cover and arranged beneath the opening, slotted portions carried by the shutters, a carrier beneath the shutters having openings arranged opposite the slotted portions thereof, controlling means comprising a plate pivotally mounted on the carrier, pins carried by the plate and projecting through the openings in the carrier to engage the slotted portions of the shutters, the controlling means being movable to actuate the shutters, a plate for supporting the carrier and controlling means, a fork mounted on the controlling plate, a handle, and means movable with the handle and coöperating with the fork to effect movement of the controlling plate.
8. In a vapor lamp, the combination with a lamp body and a cover having an opening therein, of a pair of shutters pivoted to the cover and arranged beneath the opening, slotted portions carried by the shutters, a carrier beneath the shutter having openings arranged opposite the slotted portions of the shutters, controlling means comprising a plate pivotally mounted on the carrier, pins carried by the plate and projecting through the openings in the carrier to engage the slotted portions of the shutters, the controlling means being movable to actuate the shutters, a plate for supporting the carrier and controlling means, and a handle operatively connected to the controlling plate.
